UNITED STATES PATENT OFFICE.

JAMES B. PLATT, OF BALTIMORE, MARYLAND.

CAN.

1,035,634.

Specification of Letters Patent. Patented Aug. 13, 1912.

Application filed July 1, 1911. Serial No. 636,449.

To all whom it may concern:

Be it known that I, JAMES B. PLATT, a citizen of the United States, residing at Baltimore city, State of Maryland, have invented certain new and useful Improvements in Cans, of which the following is a specification.

My invention relates to improvements in cans or receptacles for fruits, oysters, liquids, and other suitable materials; and its object is to improve upon the means for closing the can.

Another object is to enable the can or other receptacle to be closed by means of a frictional spring-top closure which affords a tight seal without the use of solder.

Further objects of the invention will hereinafter appear; and to these ends the invention consists of a device for carrying out the above objects embodying the features of construction, combinations of elements, and arrangement of parts having the general mode of operation substantially as herein-after fully described and claimed in this specification and shown in the accompanying drawings, in which;

Figure 1 is a view in side elevation of a can constructed in accordance with this invention, and Fig. 2 is a sectional view on an enlarged scale through the can and cover.

Reference being had to the accompanying drawings, A represents a can or other receptacle, made from any suitable material, preferably sheet metal, provided near its upper end portion with a laterally extended angular V shaped bead 1, below which is provided an annular bead 2, the upper edge of the can above the bead 1 being rolled or curled inwardly to form an annular bead 3, the bead 3 being reinforced with a wire ring 4, for the purpose of rendering the mouth of the can rigid.

The sheet metal cover B is provided with a depending flange 5, the lower edge of the flange being curled or rolled outwardly forming an annular bead 6, this bead being also reinforced with a wire ring 7 similar to that of the bead 3; provided in the wall of the flange 4, and predeterminedly located above the bead 6, is provided an angular V shaped groove 8, adapted to engage with the angular bead 1 on the can, when the cover B is placed on the can and downward pressure applied upon it; the downward pressure on the cover will cause the groove 8 to spring over the bead 1, and become locked

over the same, and thereby secure the cover tightly on the can.

The cover being made from resilient material, preferably, sheet metal, but little pressure is required upon the cover to force the groove 8 over the bead 1, and when forced over the bead, the groove will spring back into locking contact with the bead with which it will engage, and the spring pressure in addition to the friction between the parts serve to secure the cover tightly on the can. According to the construction described it will be seen that the cover may be readily removed by leverage, by the use of a tool the cover may be sprung off the can, it being only necessary to apply leverage to a suitable tool or instrument inserted under the bead 6 of the cover, between the flange 5 and the can, in which case the cover is easily pried off. The object of the annular bead 2 is twofold, one object being to stiffen the can at this point, the other, and most important object however, being to limit the insertion of the cover on the can.

Obviously some features of this invention may be used without others and the invention may be embodied in widely varying forms. Therefore being aware that slight changes and alterations might be resorted to in the form and arrangement of the several parts described, without departing from the spirit and scope of my invention, hence I do not wish to limit myself to the exact construction as herein set forth; but,

Having fully described my invention, what I claim as new and desire to secure by Letters Patent, is:

1. The combination in a can of the character described having an angular V shaped bead laterally formed in its upper end portion, of a cover having a depending flange with an angular V shaped groove provided therein to receive the bead on the can when the cover is placed thereon and thereby seal the same, substantially as described.

2. The combination in a can of the character described the upper edge of which is rolled or curled inwardly to form a bead, a metal ring provided in the bead, an annular bead laterally provided below the mouth of the can, of an angular V shaped bead laterally formed and interposed between the annular bead and the mouth of the can, a cover therefor formed with a depending flange having an annular bead formed on the edge thereof, and an angular V shaped

groove formed in said flange above said bead, to receive the angular V shaped bead on the can, and thereby seal the same, substantially as described.

- 5 3. The combination in a can of the character described, having an angular V shaped bead laterally formed in its upper end portion, of a cover having a straight depending flange with an angular V shaped groove

provided therein to receive the bead on the can when the cover is placed thereon, substantially as described.

In testimony whereof I affix my signature in presence of two witnesses.

JAMES B. PLATT.
